UNITED STATES PATENT OFFICE.

HERMAN L. STRONGSON, OF SPRINGFIELD, MASSACHUSETTS, ASSIGNOR TO LOEB-STRONGSON CORPORATION, OF NEW YORK, N. Y., A CORPORATION OF NEW YORK.

POURING-SPOUT.

1,355,010.

Specification of Letters Patent.

Patented Oct. 5, 1920.

Application filed June 5, 1919. Serial No. 301,905.

To all whom it may concern:

Be it known that I, HERMAN L. STRONGSON, a citizen of the United States, and a resident of Springfield, county of Hampden, 5 and State of Massachusetts, have invented a new and Improved Pouring-Spout, of which the following is a full, clear, and exact description.

This invention relates to pouring spouts. 10 More particularly the invention discloses a device which may be applied to a sealed tin, or applied to any form of can which contains liquids to be decanted for the purpose of pouring the liquid from the can 15 through a specially prepared spout, and kept covered by a closure cap.

An object of the invention is to provide a pouring spout fitted with a puncturing or cutting blade so that the pouring spout 20 may be quickly inserted in the can and securely clamped thereto. It is a purpose of the invention to provide a pouring spout which will be sanitary in use and which will be closed at all times when the liquid is not 25 being poured.

A particular object of the invention is to provide a pouring spout fitted with a puncturing blade, the design of which is so arranged as to tightly clamp the pouring 30 spout against the top of the can so as to form a liquid-tight joint between the can and the pouring spout.

With the above principal objects, and others, in view, the invention has relation to 35 a certain combination and arrangement of parts, an example of which is described in the following specification, pointed out in the appended claims, and illustrated in the accompanying drawings, wherein:

40 Figure 1 shows the pouring spout fixed to a can tilted up in service or pouring position.

Fig. 2 shows a vertical sectional view taken through the pouring spout with the 45 plane of the section taken parallel with the plane of the puncturing blade.

Fig. 3 shows a vertical sectional view taken through the pouring spout tube, the section plane taken right angularly with 50 the plane of the puncturing blade, with said blade removed.

Fig. 4 shows a detailed view of a certain puncturing blade employed in connection with the tubular pouring spout.

55 In constructing a pouring spout under the specifications and claims of this dis-

closure, I employ a tubular member fitted with a puncturing blade, and provide means for securing a positive liquid-tight joint between the can and the pouring 60 spout. The device is applied to the can and permanently left thereon during the period of use of the contents of the can.

In the drawings, a tubular member is shown which comprises an approximately 65 round bottom end and flange 5. This round end is provided with shoulder portions 6 formed by cutting upwardly from the face of the flange. Slots 7 are cut in the wall of the tubular member adjacent the shoulder 6. The upper portion of the pouring spout is designated by the numeral 8 and is flattened so as to be approximately rectangular in cross section. The drawings show the round lower end of the tube with 70 the flat upper extremity. The upper end of the pouring spout is provided with a shoulder 9 formed on each side of the tubular member. The shoulders 9 are formed upon an upper flat portion of the tube while the 75 shoulder 6 is of cylindrical form and cut in the lower round portion of said tube. The tubular member is provided with a small indenture, drilled cavity or cast cavity 10 formed in the upper corner of said tube 80 above the shoulders 9 and within each side wall of the tubular member.

A puncturing blade 12 is integrally formed with a cross bar 13. This cross bar 13 is enlarged on each end as designated by 90 14. The enlarged portions 14 thus form shoulders 15 so as to provide a substantially narrow bar member 13 with substantially wide ears or broad portions 14. This cutting blade has downwardly inclined cutting edges 16 which converge to a point and thus form a sharp tapered cutting member. The cutting edges 16 are terminated by the 95 upwardly inclined clamping edges 17. The edges 17 are formed on an angle so as to join the bar 13 at an angle. The function of the upwardly inclined clamping edges 17 will appear as the description proceeds. The blade 12 is assembled with the tubular member by fitting the ears 14 thereof into 100 the oppositely disposed slots 7. The blade bar is pressed into the slots and retained therein by inherent friction or made secure by riveting over the metal forming the slots so as to lock the bar therein. The broad 105 portions or ears 14 thus provide the puncturing blade with ample engaging surface 110

fitted within the slots so that the puncturing blade can not be turned or loosened therein. The shoulders 15 forming the projecting ears thus space the underneath edge 5 of the bar somewhat above the face of the flange. This construction disposes the puncturing blade 12 centrally within the round lower end of the tubular member, and thus leaves the tubular member open and unobstructed so as to admit the flow of liquids 10 past the puncturing blade into the tubular member.

A gasket 18 of any appropriate material such as pliable and yieldable rubber is inserted 15 in the bore forming the shoulder 6. This gasket will be pressed into the bore so that its walls will expansively engage the shoulder to retain it in position. Shellac, cement or other adhesive material may 20 be employed for securing the gasket in position. The thickness of the gasket will be somewhat greater than the depth of the groove forming the shoulder so that said gasket will project from the face of the 25 flange of the tubular member. This gasket is employed for the purpose of forming an air-tight and liquid-tight joint between the can and the pouring spout or tubular member.

30 A cap or cover is used for closing the upper end of the pouring spout when the device is not in service. This cover comprises a flat sheet metal member provided with integrally down-turned parallel sides 20 35 formed from the top plate portion 21. The upper plate portion 21 projects beyond the sides forming trip or finger pieces 22. The cover side pieces 21 are punched or indented at 24. This punched-in portion 24 is provided upon each side piece 20 and registers with the indented cavity 10. This hinges the cover member on the upper portion of the tube and effectually closes that tube. The lower edges of the side pieces 20 lay 40 in engagement with the shoulders 9. This construction forms an exterior smooth and flush finish between the surface of the cover and the surface of the flat portion of the tubular member. The finger pieces 22 project just sufficiently to admit of the user's 45 fingers engaging said projections for the purpose of hinging the cover about its pivotal point 10. Either front or rear finger portions may be used. It may be preferable 50 to form the cover cap even or flush on the front end and provide the rear end thereof with the finger trip 22 so that slight pressure thereupon will tilt the cover about the pivotal point 10 for opening the tubular member.

In use, this pouring spout will be grasped by the tubular member and thrust through the center of a milk tin or other sealed container so that the blade 12 punctures the 55 top thereof and brings the gasket 18 into

compressive engagement with the outer surface of said can. The upper flat portion of the tubular member may be grasped between the thumb and forefinger of the person and the whole device given a one-quarter turn. The upper flattened portion of the tubular member renders it easy and convenient for grasping within the person's hands. A substantial and strong turning grip can be had against the upper flattened 75 end of the tube which permits the person to easily give it the necessary one-quarter turn. This causes the cut ends of the punctured tin to curl downwardly along the beveled edges 17 of the blade. This exerts a 80 clamping action by forcing the instrument downwardly against the surface of the can when the punctured tin edges 25 creep downwardly along the inclined edges 17 thus compressively engaging the gasket 18 85 against the surface of the can. The edges 25 curl downwardly along the edge 17 and effectuates the clamping action. The device is especially designed to leave sufficient space between the surface of the can and the 90 adjacent edge of the bar so as to leave room to draw the blade and bar downwardly without contacting the can surface. This function is illustrated in Fig. 2.

This pouring spout may be left in position upon the can as long as the contents are to be used and will thus provide an adequate pouring means for decanting the liquids therefrom, and further provide a positively sealed can when the cover plate is 100 in downwardly closed position.

Having thus described my invention, what I claim as new, and desire to secure by Letters Patent is:

1. A pouring spout for cans, comprising 105 a tubular member, said member having a recess formed in one end thereof, a bar anchored in the tubular member back of the recess, a gasket fitting into the recess over the bar, and a blade fixed to and extending 110 from the bar which coacts with the gasket to clamp the pouring spout on a can.

2. A pouring spout for cans, comprising 115 a tubular member, said member having a recess formed in one end thereof, a bar anchored in the tubular member back of the recess, and a blade fixed to and extending from the bar.

3. A pouring spout for cans, comprising 120 a tube flattened at one end to provide a convenient hand grip, a recessed flange formed on the other end of the tube, a gasket fitted into the recess, a bar anchored in the tube back of the recess and gasket, a spear shaped blade fixed to and extending from the bar 125 and coacting with the gasket to clamp the spout on a can and form a fluid tight joint between the pouring spout and can.

HERMAN L. STRONGSON.
